UNITED STATES PATENT OFFICE.

WILLIAM S. REEDER, OF ST. LOUIS, MISSOURI.

SHIFTABLE STACKER.

SPECIFICATION forming part of Letters Patent No. 399,211, dated March 5, 1889.

Application filed April 27, 1888. Serial No. 272,057. (No model.)

To all whom it may concern:

Be it known that I, WILLIAM S. REEDER, a citizen of the United States, residing at St. Louis, in the State of Missouri, have invented 5 certain new and useful Improvements in Shiftable Stackers, of which the following is such a full, clear, and exact description as will enable any one skilled in the art to which it appertains to make and use the same, reference 10 being had to the accompanying drawings, forming part of this specification.

My invention relates more particularly to shiftable stackers that are applicable to shuck-corn shellers, thrashers, and the like.

15 The invention consists, primarily, in a universal or flexible shafting of the character described between the stationary power-shaft and the carrier-driving mechanism that revolves with the shiftable stacker.

20 It consists, also, in certain details of construction, which will now be set forth in detail, and the novel features thereof particularly pointed out in the claims making a part hereof.

25 Figure 1 is a perspective view of my stacker applied to a corn-sheller. Fig. 2 is an elevation of the mechanism that drives the carrier, showing a flexible slotted link-shafting. Fig. 3 is a plan of the latter, the upper half 30 of the same being removed; and Fig. 4 is an isometric projection of a portion of the flexible slotted link-shafting.

The same figures of reference indicate the same parts throughout.

35 1 is the rotary shaft, that is driven by a pulley, 2, rotated by a belt which has power applied to it by any suitable rotary part of a machine.

30 3 is the shiftable stacker, which is supported by offsets 4 4 and cord 5, attached to the top of the machine. The offsets 4 4 are supported by pillars 6 6, which are sustained by cross-pieces 7 8, that bear upon a circular table, 9, together forming a turn-table, which 45 is supported upon the front part of the machine by a flange, 10, that carries a bearing for the driving-shaft 1. The lower part of the offsets 4 4 are fashioned into boxes, in which shaft 17, to be hereinafter described, is 50 journaled. These boxes are in turn journaled in the upper part of the pillars 6 6, so that the stacker can be raised or lowered. The

pillars 6 6 are screw-threaded at their lower ends, and are screwed to the cross-piece 7 by nuts on each side of the same, whereby they 55 can be raised or lowered. The table 9 is provided with a rim, 11, upon which the cross-pieces bear. The cross-pieces 7 8 are pivoted at the center of the table 9, which has also a rim, 12, near its center for the cross-pieces 7 60 8 to bear upon near the pivot.

13 13 are the ears by which the table and flange 10 are secured to the machine. From the shaft 1 extends a universal slotted link-shafting, 14, to a sprocket-wheel, 15, which is 65 journaled in a downward extension, 16, of the cross-piece 7.

Through the boxes of the offsets 4 4 passes a shaft, 17, carrying a sprocket-wheel, 18, which drives the carrier 19, that removes the 70 cobs or straw from the stacker, said carrier being made up of a sprocket-chain having cross-pieces attached thereto, as is usual. Upon the end of the shaft 17, just over the sprocket-wheel 15, is another sprocket-wheel, 75 20. Between the sprocket-wheel 15 and the sprocket-wheel 20 is a sprocket-chain, 21. When the shaft 1 is rotated, it drives the sprocket-wheel 15 by means of the flexible slotted link-connection, which sprocket-wheel 80 15 actuates the sprocket-wheel 20 through the instrumentality of the sprocket-chain 21, and thus drives the sprocket-wheel 18, which in turn drives the carrier 19 to remove the cobs and shucks. Should the stacker be revolved 85 by hand to a second position, this will revolve the cross-pieces 7 8 and the driving mechanism about the pivot as a center, so that some means has to be devised to give the shafting between the sprocket-wheel 15 and the stationary shafting 1 flexibility, and this is the 90 principal feature of my invention.

My flexible shafting is made up, preferably, of two series of links, 22, 23, and 24, the link 22 being provided with pins engaging slots in 95 the link 23, and the link 24 being provided with slots which are adapted to receive the pins of a second pin-link. (See Fig. 4.) The link 24 and the link 23 are in fact one link, as they are made in one piece. The slot and pins allow great play and flexibility of this link-shafting, so that the stacker may be moved through a quadrant without interfering with the operation of the driving mech- 100

anism. It will be seen, therefore, that the stacker may be swung round at any angle up to ninety degrees without interfering with the operation of the mechanism in the slightest. Should the sprocket-chain 21 become slack, the pillars 6 6 can be raised to take up the slack, or lowered to relieve the strain upon the chain, as the case may be.

Other forms of universal shafting may be used without departing from the spirit of my invention.

25 and 26 are the ordinary hinged side boards of the stacker.

Having now fully set forth my invention and described its operation, what I desire to claim and secure by Letters Patent of the United States as my invention is—

1. The combination, with a shiftable stacker, of a driving mechanism for the carrier of said stacker rigidly secured to said stacker and revolving therewith, a stationary power-shaft, and a flexible slotted shafting between said stationary power-shaft and said driving mechanism, consisting of links 22, 25 having pins projecting therefrom at right angles to each other, and a two-part link made

of slotted links 23 and 24, joined rigidly together at right angles to each other and engaging the pins aforesaid.

2. A stacker having adjustable pillars, as 6 6, between the carrier-driving shaft and the platform which carries the mechanism for actuating said shaft, for the purpose set forth.

3. The combination, with a shiftable stacker, of offsets, as 4 4, supporting said stacker and terminating in journal-boxes, pillars, as 6 6, in which said boxes have bearings, whereby the stacker can be swung up or down, a carrier for said stacker, a shaft, as 17, journaled in said boxes and carrying gearing for said carrier, a turn-table to which said pillars are adjustably secured, a gear-wheel, as 15, carried by said turn-table, a stationary power-shaft, as 1, and a flexible connection between the latter two.

In testimony whereof I have hereunto set my hand, this 21st day of April, 1888, in the presence of the two subscribing witnesses.

WM. S. REEDER.
